(57) **CLAIM**

The ornamental design for a console for a book or other similar article, as shown and described.

DESCRIPTION

FIG. 1 is a perspective view of a console for a book according to the invention;

FIG. 2 is a left side, elevation view of the console.

FIG. 3 is a right side, elevation view of the console.

FIG. 4 is a rear, elevation view of the console.

FIG. 5 is a front, elevation view of the console.

FIG. 6 is a top, plan view of the console; and,

FIG. 7 is a bottom plan view of the console.

The broken lines in FIGS. 1–7 showing environmental structure form no part of the claimed design. FIG. 3 shows the pages (in broken lines) of the book when the book is closed. FIG. 5 shows the pages (in broken lines) of the book when the book is opened to show the claimed console more clearly.
